SPRINKLER RELEASING MEANS

Ira W. Knight, Providence, R. I., assignor to
 Grinnell Corporation, Providence, R. I., a corporation of Delaware

Application December 9, 1943, Serial No. 513,575.

2 Claims. (Cl. 169—39)

This invention relates to improvements in sprinkler releasing means. More especially it has to do with means which permits the normal opening of an automatic sprinkler upon the giving way of its own thermoresponsive element and by which the sprinkler may be opened in response to other thermoactuated means, or opened manually.

In the art of fire protection the usual automatic sprinkler head is provided with a thermally responsive element which normally holds the sprinkler closed but which is adapted to give way at some predetermined temperature to effect opening of the sprinkler for fire extinguishing discharge. Such a head is placed in a location where fire is apt to occur in its vicinity. When this happens and creates a sufficient temperature to cause its thermoresponsive element to give way, the sprinkler is opened for extinguishing discharge upon the fire. It has been found advisable in some instances to have a sprinkler open and discharge to occur therefrom primarily as a protective measure to prevent the spread of a fire which starts at some place where the heat therefrom would not promptly affect the thermoresponsive element of the sprinkler. An example of such a situation is found in the case of an air cleaner through which air is passed over oil-covered surfaces. If a fire occurs outside the cleaner it is highly desirable to prevent its spread to such surfaces where it could ignite the oil and readily destroy the cleaner. Another example may be found in the case of a tank containing flammable fluid. If a fire occurs near the tank the contents thereof may be protected by discharge of a suitable protective medium upon the flammable fluid before it becomes ignited. In all such cases where such a protective discharge is desirable it is of course imperative that the sprinkler be opened by response of its own thermoresponsive element should the fire occur in its immediate vicinity.

It is therefore among the objects of this invention to provide releasing means which will permit the normal opening of a sprinkler head by the giving way of its own thermoresponsive element, which will effect the opening of the head upon the giving way of another thermoresponsive element not a part of the means normally holding the sprinkler closed, and which, if desired, will enable a sprinkler to be opened by hand.

The best mode in which I have contemplated applying the principles of my invention is shown in the accompanying drawing, but these are to

be deemed merely illustrative for it is intended that the patent shall cover by suitable expression in the appended claims whatever features of patentable novelty exist in the invention disclosed.

In the accompanying drawing:

Figure 1 is an elevation of an automatic sprinkler head, in the usual upright position, having a thermoresponsive element holding the sprinkler closed and adapted to give way upon being heated to a predetermined temperature, together with means for otherwise removing this element from its sprinkler closing position;

Figure 2 is a view like Figure 1 suggesting the position of certain parts during an opening of the head;

Figure 3 is a view of a pendent sprinkler;

Figure 4 is a perspective view, partly in section, of means associated with the sprinkler head for effecting the removal of its thermoresponsive element mechanically; and

Figure 5 is a medial section showing details.

Referring to the drawing, the sprinkler shown is very much like the head disclosed in Letters

Patent No. 2,085,987, granted July 6, 1937. The sprinkler body or frame 1 has a nozzle 2 exteriorly threaded for engagement with a supply line 3 carrying fluid under pressure, and has a yoke 4 at the top of which is a deflector 5.

Prior to discharge the fluid is held back by a valve 6 which is held to its seat on the sprinkler frame at the upper end of the nozzle by means embodying a thermoresponsive element. In the sprinkler shown here for illustrative purposes this element is a frangible bulb 7 which rests upon a flanged cap 8 within which is housed resilient means (not shown). As disclosed in the aforesaid patent, the upper end of the bulb rests against a suitable recessed cylindrical washer interposed between the bulb and a locking pin protruding through the top portion of the yoke.

In carrying out my improvements I provide a lever-washer 9 which serves both as a seat for the bulb 7 and as a pry for removing the bulb and thereby destroying the strut holding the sprinkler closed. This element (see Figure 5) has near one end surfaces 9a and 9b on its opposite sides which afford suitable seats for a cushion ring 1a for the bulb 7 and for a locking pin 10 secured in the top portion 4a of the yoke 4. At its other end is an angularly disposed portion 9c having a hold 9d for reception of a tie element such as a hook 11.

When the sprinkler head is installed upright, that is with the deflector 5 uppermost as shown

in Figures 1, 2 and 4, the lever-washer is arranged with its angularly disposed portion $9c$ extending toward the deflector. If, however, the head is used as a pendent sprinkler, with the deflector lowermost as in Figure 3, then the position of the lever-washer is reversed so that its portion $9c$ extends away from the deflector.

If a fire occurs in the neighborhood of the sprinkler so that heat therefrom will raise the temperature of the bulb 7 and its contained charge to some predetermined degree, the bulb will be destroyed and the sprinkler opened for fire extinguishing discharge. Thus the head will be opened in the usual manner of automatic sprinklers.

It may be, however, that although a fire starts too far from the sprinkler to have any effective thermal influence upon it, the nature of the risk may be such that it is advisable to open the sprinkler for a protective discharge therefrom. This may be accomplished manually with my improved means by pulling on a tie attached to the extended portion $9c$ of the lever-washer. Such a pull will cause the lever-washer to rotate, as it were, about the end of the locking pin 10 and pry the bulb away from its normal position, in the manner suggested in Figure 2. In this opening of the head, the frangible bulb 7 is not necessarily shattered but is nevertheless removed thus releasing the strut. The lever-washer is pulled away and the medium under pressure in the supply pipe to the sprinkler dislodges the cap 8 , the resilient means therein housed, and the valve 6 .

Instead of manually opening the sprinkler, my invention contemplates the automatic opening of the head albeit its own thermoresponsive element does not give way because of any change in temperature. The sprinkler may be located within an inclosure, such as a room, casing, tank, etc., and it may be desirable to effect its opening when a fire occurs outside such inclosure. In Figure 4 I have illustrated means for so opening the head for protective discharge.

The plate 12 may be taken as representing the wall of an inclosure through which extends a supply pipe 3 to a sprinkler head 1 . Attached to the wall on the side remote from the sprinkler is a bracket 13 having associated therewith tubular members 14 and 15 . One of these (14) extends through the wall and is so disposed that a tie 16 attached to the washer-lever 9 of the sprinkler can readily be pulled in a direction that will effect the opening of the head. This tie 16 is fastened to a weight 17 which is held in the inactive position illustrated by another tie 18 at-

tached thereto and extending through the other tubular member 15 and thence to a thermoresponsive link 19 , adapted to give way upon being heated to a predetermined temperature. Still another tie 20 extends from the link 19 to some secure fastening. Although I have only shown one link, it is to be understood that others might be in the tie as a whole extending from the weight 17 to the ultimate anchor for the tie.

10 Upon a fire occurring outside the inclosure and near enough to a link 19 to cause the latter to give way, the weight 17 will upon being thus released drop downward and impose a sudden jerk on the tie 16 . This is transmitted to the lever-washer 9 whereupon the latter pries loose the bulb 7 and effects opening of the sprinkler for protective discharge within the inclosure.

I claim:

1. Sprinkler releasing means comprising thermoresponsive means normally holding a sprinkler closed and adapted upon being heated to a predetermined temperature to give way and effect the opening of the sprinkler, and a lever-washer interposed between the thermoresponsive means and the frame of a sprinkler normally serving as a seat for said thermoresponsive means and adapted to serve as a lever to pry said thermoresponsive means from its sprinkler closing position; the said lever-washer having seats on its opposite sides to permit the lever to be interposed between the thermoresponsive means and the sprinkler frame in either of two positions to accommodate selectively a force acting on the lever in either of substantially opposite directions with respect to the sprinkler frame.

2. Sprinkler releasing means comprising a frangible bulb normally holding the sprinkler closed and containing a charge adapted upon being heated to a predetermined temperature to destroy said bulb and thereby effect the opening of the sprinkler, and a lever-washer interposed between one end of said bulb and a locking pin in the frame of a sprinkler capable upon being subjected to an externally applied force of prying said bulb from its sprinkler closing position irrespective of the temperature of said charge; the said lever-washer having seats on its opposite sides with each seat being formed to engage either the locking pin or the bulb, whereby the lever-washer may be reversibly positioned to accommodate an external force applied to the lever-washer in either of substantially opposite directions with respect to the sprinkler frame.
